UNITED STATES PATENT OFFICE.

FREDERICK C. BLOOM, OF NORWOOD, OHIO.

DISPLAY STAND.

1,416,935.

Specification of Letters Patent. Patented May 23, 1922.

Application filed January 11, 1922. Serial No. 528,478.

To all whom it may concern:

Be it known that I, FREDERICK C. BLOOM, a citizen of the United States, residing at Norwood, in the county of Hamilton and State of Ohio, have invented certain new and useful Improvements in Display Stands, of which the following is a specification, reference being had to the accompanying drawings.

10 This invention relates to display stands and more particularly to a rotatable display stand which is capable of being folded and stored in a small space.

An important object of the invention is to 15 provide a structure of this character which may be very cheaply manufactured and in which the shelves tend to brace and space the supporting arms upon which they are mounted.

20 A further object of the invention is to provide a novel and efficient shelf mounting for use in this type of structure whereby the result above referred to may be accomplished.

25 A still further object of the invention is to provide a device of this character which may be readily disassembled without the necessity of employing a tool.

Other objects and advantages of the invention 30 will become apparent throughout the course of the following description.

In the accompanying drawings, wherein for the purpose of illustration I have shown a preferred embodiment of my invention, 35 and wherein like reference characters designate like parts throughout;

Figure 1 is a vertical sectional view taken through a display stand constructed in accordance with my invention;

40 Figure 2 is a plan view thereof, certain of the shelf sections being removed;

Figure 3 is a perspective view illustrating the manner of folding the braces; and

45 Figure 4 is a perspective view showing the construction of the shelf mounting.

Referring now more particularly to the drawings, the numeral 10 designates a base or stand upon which is rotatably mounted a vertical standard 11. In the present embodiment of my invention, the standard 11 comprises a cap 12 rotatably seated upon the base 10 and having extending upwardly therefrom a tubular vertical member 13. The base 10 is provided with an upstanding post 14 entering the lower end of the tubular member 13 and preventing accidental re-

moval of the cap 12 and the standard 11. The upper end of the tubular member 13 slidably receives the lower end of an extension member 15 which is held in adjusted 60 position by means of a set screw 15^a. The upper end of the extension member 15 is provided with a head 16 upon which may be mounted, if so desired, a further vertical extension 17 bearing a display support 18. 65 To the head 16 is pivotally secured as at 19, a plurality of equidistantly spaced arms 20 which extend downwardly from the head and are held in the desired position by a brace 21 pivotally connected to the arms 20 70 adjacent the lower ends thereof which braces in turn abut the cap 12 with their lower ends. To each of the arms 20 is secured a plurality of shelf supports A. The number of shelf supports secured to each arm, is 75 of course, governed by the use for which the display stand is employed. Where the stand is used for the display of flowers, I prefer the use of a pair of these supports, one adjacent the upper end of the arm and 80 one adjacent the lower end thereof. Each of the supports A comprises a pair of members 22 secured to opposite sides of the arm 20, as at 22^a, and a brace 23 secured at its lower end to the arm 20 at a point below the 85 securing point of the members 22 thereto and having its upper end secured to the free ends of the members 22 in such manner that this upper end extends above the upper surface of the members 22, as indicated at 24. 90

The shelves S are formed in sections 25, each of a length to extend from the support A of one of the arms to the support A of the next adjacent arm, and rest upon the members 22 upon the adjacent side of the adjacent arms, each end of each shelf section 25 being notched as at 26 to partially admit the upwardly projecting ends of the brace members 23. From the foregoing, taken in connection with an inspection of the drawings, 95 it will be noted that the brace members 23 not only serve to support the members 22 and therefore the shelves, but they likewise serve to prevent outward movement of the shelf sections and the shelf sections and 100 braces combine to maintain the arms and particularly the lower or free ends of the arms against lateral displacement such as would admit of the shelves being loosened from their supports. When it is desired to 105 fold the stand, this may be accomplished by folding the members 22 upwardly, at their 110

pivotal connection with the arms 20 and removing the shelf sections 25, permitting the arms 20 to hang downwardly from their pivots 19. The entire assembly of the stand 11 and arms 20 may then be removed from the base and stored at any desired point.

From the foregoing it is believed to be obvious that I have constructed a display stand which is particularly well adapted for use for which it is intended by reason of the fact that it may be readily and cheaply manufactured and by reason of the fact that the parts thereof coact, so as to render the completed structure strong and rigid without the necessity of permanently connecting the parts. It will furthermore be obvious that many changes may be resorted to in the shape, size and arrangement of the various parts herein shown, without in any manner departing from the spirit of my invention and the scope of the subjoined claims.

What is claimed is:—

1. In a stand of the type described, a rotatable support, a plurality of arms pivotally connected at their upper ends with said support, shelf supports carried by each of said arms and a brace having a portion extending above the upper surface of the shelf support

likewise carried by each arm, and shelf sections disposed intermediate adjacent arms and having their ends supported by corresponding supports thereof, the ends of said shelf sections being each provided with a notch partially receiving the portions of said braces projecting above the upper surface of the supports.

2. In a stand of the type described, a rotatable support, a plurality of arms pivotally connected at their upper ends with said support, shelf supports carried by each of said arms and each comprising a pair of members arranged upon opposite sides of the arm and extending outwardly therefrom, and a brace secured to the arm at its lower end and at its upper end to said members, the upper extremity of the brace extending beyond the upper surface of said members, and shelf sections disposed intermediate adjacent arms and having their ends supported by the members upon adjacent sides of the arms, the ends of said shelf sections being each provided with a notch partially receiving the portion of said braces projecting above the upper surface of the support.

In testimony whereof I hereunto affix my signature.

FREDERICK C. BLOOM.
